CLAIM

The ornamental design for a glass lintel for supporting doors, as shown and described.

DESCRIPTION

FIG. 1 is a perspective view of a glass lintel in accordance with the present design;

FIG. 2 is a perspective view of the glass lintel of FIG. 1;

FIG. 3 is a front elevation view of the glass lintel of FIG. 2, the rear elevation view being a mirror image thereof;

FIG. 4 is a right-side elevation view of the glass lintel of FIG. 2, the left-side elevation view being a mirror image thereof; FIG. 5 is a top plan view of the glass lintel of FIG. 2; and,

FIG. 6 is a bottom plan view of the glass lintel of FIG. 2.

The broken lines in some figures are for illustrative purposes only and form no part of the claimed design.
